(57) **CLAIM**

The ornamental design for a computer hub as shown and described.

DESCRIPTION

FIG. 1 is a top, front, and right perspective view of a computer hub showing our new design;

FIG. 2 is a bottom, rear, and left perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof; and,

FIG. 9 is a top, front, and right perspective view of the computer hub shown in a state of use with additional environmental cord and laptop.

The broken lines in FIG. 9 showing the cord and laptop depict unclaimed environmental subject matter only and form no part of the claim, while all other broken lines depict portions of the computer hub that form no part of the claimed design.

1 Claim, 9 Drawing Sheets
